UNITED STATES PATENT OFFICE.

LELAND G. PLANT, OF CHICAGO, ILLINOIS.

HOSTLING AND COALING STATION FOR LOCOMOTIVES.

Application filed August 1, 1924. Serial No. 729,451.

To all whom it may concern:

Be it known that I, LELAND G. PLANT, a citizen of the United States, residing at Chicago, in the county of Cook and State of Illinois, have invented certain new and useful Improvements in Hostling and Coalizing Stations for Locomotives, of which the following is a specification.

This invention has for its object to provide at relatively low cost, a simple mechanical fire drawing, ash disposal, coal supplying and locomotive charging means that can be inexpensively and reliably operated at intermediate points in a division, at terminals on divisions where the traffic is small, and in any other situation where only a small number of locomotives are kept available and the maintenance of more complete hostling facilities would be uneconomical; whereby, for the sake of economy, expensive overhead storage and distribution, and sublevel ash conveying, as a means of restoring locomotives to service, can be dispensed with, and replaced by means for keeping coal constantly flowing to the locomotives from a distant point of supply and for keeping ashes moving from the locomotives to a distant point of disposal; and whereby, for the sake of quick restorative, such coal supply and ash disposal may be carried on without interruption, other than that incident to the operation of the transfer means, and without expenditure for manual labor, or delay incident to unloading coal supplying cars that are not self cleaning or manually dislodging frozen coal in cars, whether of the dumping or non-dumping type.

The invention proceeds upon the principle of providing a stationarily mounted or otherwise locally established elevating and conveying apparatus, for instance a radial crane having a bucket serving in common for transfer of both fuel and ash refuse; a track for locomotives to be treated, having a fire refuse, by gravity, from a locomotive on said track and to admit the elevating bucket from above for removal of said refuse; also a coal unloading and refuse loading track equipped with a coal pit, which coal pit is positioned to receive coal, by gravity, from a car standing on the unloading and loading track and also to admit from above the bucket of the

conveying and elevating apparatus, said unloading and loading track being also adapted to present a car in position to receive ashes from said bucket; the coal pit, the coal-laden car over said pit, the ash-receiving car, the ash-receiving pit, and the tender attached to a locomotive that is over the ash pit, being all within the orbital path of the elevating and conveying bucket, or sufficiently near to be served by the bucket; and the construction and arrangement is such that a locomotive may be brought into the station and have its fire quickly cleaned, and its tender coaled simultaneously, coal cars may be brought in and kept in position for immediate transfer of their coal, or so much thereof as can be removed by grab-bucket, directly to the locomotive tender; a coal car can have the remnant of its load or whole load dumped in case the car is needed for ashes or required to be moved from the coal pit for any other reason; a flat bottom car that is not self dumping can be unloaded by means of the vertically accessible grab-bucket so as to largely eliminate the manual labor ordinarily involved in unloading these cars and coal that does not readily empty itself through the bottom doors of self dumping cars can be more easily dislodged and caused to flow by the vertical impact of said vertically accessible bucket; a provisional supply of coal will always be on hand in and removable by the bucket from the pit in the absence of a coal car; and a supplementary or emergency stock of coal can be accumulated in a pile on the ground space between said coal pit and the locomotive track; ashes can be disposed of and conveyed away as fast as they accumulate, or provisionally stored on the ground space between said ash pit and the ash car loading track, particularly during the interval between the hostling of locomotives; and the whole service, including the shifting of cars if need be, can be performed by a single elevating and conveying apparatus of very simple construction.

In order that the invention may be fully understood, the preferred embodiment thereof has been illustrated in the accompanying drawings, in which

Figure 1 is a sectional elevation of a sta-

tion embodying the several features of the invention, the plane of section being transverse to the two tracks,

Figure 2 is a plan view of the arrangement shown in Figure 1, and

Figure 3 is an elevational view to be had from the right of Figures 1 and 2.

Figure 4 is a view corresponding to Figure 2, but showing a duplicate of the fire drawing pit that adapts the station to serve locomotives entering the station in either direction.

1 represents a radial crane mounted upon a fixed base 2 and having a boom 3 equipped with a grab-bucket 4 which, by reason of the reach and rotation of the crane 1, has an orbital path within which it is adapted to act upon subdivided material for picking up, conveying and depositing the same as may be required. 5 represents a locomotive track adapted to present a locomotive 6 in position where its fire chute 7 can discharge into an ash pit 8 and the latter is provided with an opening 9 through which it may receive the bucket 4. Ash pit 8 and locomotive track 5 are so located that when a locomotive has a position on said track, which adapts the locomotive to discharge its fire into the ash pit, a tender 10 attached to the locomotive will be sufficiently near the orbital path, to bring them within a discharging position of the bucket 4. 11 represents an unloading and loading track for cars bringing in coal and taking away ashes, and 12 represents a coal receiving pit positioned relatively to the track 11 to receive, by gravity, coal brought in by a car 13 upon said track. The coal pit 12 and track 11 are so located relatively to the orbital path of action of the bucket 4 that the bucket may dip into the pit 12 to pick up coal to be conveyed to the tender 10 or dip into the car 13 occupying a position over this pit, when it is desired to transfer coal directly from the car to the tender; and another car 14 (Figure 2) may simultaneously or subsequently stand upon the track 11 in a position to receive ashes transferred by the bucket 4 from the ash-pit 8. The ash-pit 8 and the coal pit 12, in the arrangement here described are required to have but relatively small capacity as they need serve only provisionally or temporarily to contain their respective materials, since the crane is always in a position to transfer material from either pit to the rolling stock by which the material is conveyed away. The demand for fuel will generally be known, within such limits as will admit of transferring, for the most part, directly from the coal car 13 to the tender 10, and keeping the ash-pit clear by transfer to ash car 14, and since the ash refuse will always be less in volume than the fuel brought in, there will always be ample capacity in emptied coal cars 13 to

serve as ash-receiving cars 14 and keep the ash-pit 8 sufficiently clear of accumulation, to receive the discharge from incoming locomotives. According to Figure 4, the locomotive track 5 is provided with an additional ash-pit 8^a having bucket receiving opening 9^a, and otherwise similar to the pit 8, but positioned to receive ash discharge from a locomotive 6^a headed oppositely to the locomotive 6 of Figures 1, 2, and 3, and without taking the tender 10^a thereof out of charging range of the bucket 4 while in position for ash discharge. Figure 4 further illustrates the availability of the station for spotting a car, such as 13^a, where it may be unloaded by the crane, through its entire length and while still leaving the coal pit 12 accessible to the bucket.

In addition to serving the common purpose of transferring material to and fro between the tracks 5 and 11, the crane 1 may be employed for shifting rolling stock, and particularly cars 13 and 14, upon the track 11, so that if other loaded cars are maintained at the station they may be successively drawn to the dumping position over pit 12, by the crane 1. While locomotives may be charged largely by picking up coal directly from the cars that bring it in, the coal pit 12 is always in position to receive from the coal car 13 any coal that may remain therein which cannot be picked up by the bucket 4, and is always accessible to the bucket 4 for transfer of coal from the pit to the locomotive tender, or to the provisional storage pile above referred to, whenever the capacity of the pit is less than the quantity that should be kept on hand for use in case of emergency or failure of coal cars to arrive.

A station having hostling and coaling facilities arranged as herein described, affords means for very rapidly and inexpensively restoring to service a locomotive requiring its fire to be cleaned and its coal supply to be replenished from either self-cleaning or non-dumping cars, and thus reduce to a minimum the detention of the locomotive from its service track, which is very important under present day railway practice; and the described arrangement for accomplishing these results, by reason of its adaptability for keeping the material in motion, from the point of fuel supply, through the element of consumption, and thence to the place of ultimate disposal, eliminates the necessity for a plant or station of large, expensive dimensions.

The arrangement and relationship of elements entering into combination to produce the hostling and coaling stations herein described, including the order in which the elements occur in the orbital path of the bucket of the single stationarily mounted pick-up and conveying device, enables the accom-

plishment of a greater number of routine locomotive hostling operations with greater dispatch and less expense than has previously been attempted by any single stationarily mounted hoisting and conveying device, or could be accomplished by the same elements in a different order.

I claim:

1. A hostling and coaling station for locomotives comprising an elevating and conveying apparatus having a pick-up and discharge bucket adapted to act at points in or adjacent to a predetermined orbital path; a coal-receiving pit and an ash-receiving pit each having an opening presented upwardly in said path through which it is adapted to admit said bucket from above; a locomotive track positioned relatively to the ash pit, to adapt a locomotive to discharge its fire refuse into said pit and simultaneously to present its tender in coal-receiving relation to said bucket; and a coal unloading and ash loading track positioned relatively to the coal pit, to present a coal car in gravity delivery relation to said coal pit and simultaneously an ash-receiving car in relation to said orbital path which adapts it to receive ashes from said bucket.

2. A hostling and coaling station for locomotives comprising an elevating and conveying apparatus having a pick-up and discharge bucket adapted to operate at points in or adjacent to a predetermined orbital path; an unloading and loading track established to present a coal car in position for removal of its contents by said bucket and simultaneously to present an ash car in position to receive ashes from said bucket; a coal pit located to receive coal by gravity from a coal car on said track as aforesaid, and having an upwardly presented opening positioned in relation to said path to adapt it to admit said bucket, a locomotive track positioned relatively to said path to adapt it to present a locomotive tender in coal-receiving relation to said bucket; and an ash pit positioned relatively to said track to adapt it to receive ashes by gravity from a locomotive, when the tender attached to the locomotive is in the coal-receiving position aforesaid, said ash pit having an upwardly presented opening positioned relatively to said path to admit said bucket.

3. In a hostling and coaling station for locomotives, a stationarily mounted elevat-

ing and conveying apparatus provided with a pick-up bucket having an orbital path of operation, a locomotive track having an ash pit positioned in relation thereto to receive ashes by gravity from a locomotive stationed on said track, and at the same time adapted to admit said bucket, from above, for the removal of accumulating ashes; a loading and unloading track adapted to present cars for supplying coal to and removing ashes from the station; a coal-receiving pit positioned in relation to said unloading and loading track to receive coal by gravity from a car standing thereon, and also adapted to admit said bucket from above; said tracks and pits being positioned relatively to said elevating and conveying apparatus, to place simultaneously in the orbital path of operation of said bucket, the coal-receiving pit, a coal car while standing in dumping relation to said coal-receiving pit, an ash-receiving car on said loading and unloading track, the ash pit beneath the locomotive track, and a locomotive tender while attached to a locomotive standing over the ash pit.

4. In a hostling and coaling station for locomotives, a stationarily mounted elevating and conveying apparatus provided with an elevating and conveying bucket having an orbital path of operation, a locomotive track having an ash pit positioned in relation thereto to receive ashes by gravity from a locomotive stationed thereon, and vertically accessible to said hoisting bucket for the removal of ashes accumulating therein; a loading and unloading track adapted to support cars for supplying coal to and removing ashes from the station, a coal receiving pit positioned in relation to said unloading and loading track to receive coal by gravity from a car standing thereon, and also vertically accessible to said hoisting bucket; said tracks being positioned relatively to said hoisting and conveying apparatus, to place directly below the orbital path of operation of said bucket, a coal car on said unloading and loading track, a coal receiving pit, a locomotive tender on the locomotive track, an ash-receiving pit, and an ash-receiving car on said loading and unloading track in the order named.

Signed at Chicago, Illinois, this 30 day of July, 1924.

LELAND G. PLANT.
